PHASED ARRAY ANTENNA

This invention relates to an improved phased array antenna device comprised by an assembly of a plurality of antenna elements, and more particularly to a phased array antenna device suitable for use as an antenna mechanism for radar communication and artificial satellite communication.

Prior art phased array antenna devices of this type which have been put into practical use are ordinarily constructed as shown in FIG. 1, in the case of the parallel feed system for example. Thus, for example, denoting the number of antenna elements by r , respective antenna elements $11_1, 11_2, 11_3, \dots, 11_r$, are connected in parallel to a common source of antenna power 12 through a feeder 13 consisting of two parallel lines or a coaxial line, said antenna elements being spaced each other with equal spacings d . In this case, phase shifters $14_1, 14_2, 14_3, \dots, 14_r$ are connected in series with respective antenna elements $11_1, 11_2, 11_3, \dots, 11_r$ at their feeder terminals to cause the phases of currents flowing through respective antenna elements to successively differ by $e^{i\theta}, e^{i2k\pi d\sin\theta}, e^{i4k\pi d\sin\theta}, \dots, e^{i(r-1)k\pi d\sin\theta}$, where $k=2\pi/\lambda$, where λ represents the wavelength of the antenna current supplied from the source of antenna power 12 so that directions of scanning (in this case in the direction of θ) of respective radiated beams of electromagnetic waves as viewed from the boresight of respective antenna elements substantially coincide.

We have found that with such a prior phased array antenna device, however, unless suitable impedance matching is provided for respective antenna elements, very complicated interference phenomena are created between respective antenna elements so that it is not only difficult to cause to precisely coincide all directions of scanning of the beams of radiated electromagnetic waves from respective antenna elements, but also characteristics of the beams of the radiated electromagnetic waves are distorted to degrade the S/N ratio. Such phenomena are remarkable especially when the load (in this case respective antenna elements) changes or the frequency of the antenna current fed from the source of the antenna power varies. 158 To obviate these defects, impedance matching devices as shown in FIGS. 2A to FIG. 4 have been proposed in the past. Thus, where the feeder adapted to connect the source of antenna power 12 to antenna elements $11_1, \dots, 11_r$, is comprised by a pair of parallel lines 13_a as shown in FIG. 2A or by a coaxial line 13_b including an outer conductor 13_{b1} and an inner conductor 13_{b2} as shown in FIG. 2B, an impedance matching stub 21_a including similar parallel lines with their ends short circuited or an impedance matching stub 21_b including a coaxial line with the ends of its outer and inner conductors short circuited is connected to a suitable point along the length of the feeder 13_a or 13_b and the length l of the stub 21_a or 21_b to the short circuited ends is adjusted in the following manner. As shown in FIG. 3 where the impedance matching stub is in the form of the coaxial line 21_b , including an outer conductor 21_{b1} and an inner conductor 21_{b2} , the coaxial line is made hollow with its outer end opened and to have a length of more than one-half of the wavelength of the antenna current. A movable short-circuiting member 22 made of a conductor and having a length of more than one-half of the wavelength of the antenna current is inserted into the stub through its opened end and the short-circuiting member is mechanically adjusted in the direction of an arrow 23 or 24. Such mechanically operated impedance matching means not only requires troublesome operation but also is difficult to adjust quickly in response to variations in the load and antenna current frequency. Further, where such a single-impedance matching stub is provided for each antenna element it is necessary to cut the antenna feeder at each point where such stub is connected. To avoid such inconvenience, three stubs spaced apart from each other by one-fourth wavelength have been connected to the feeder. Although this solution is advantageous in that it is possible to provide the required matching irrespective of the length between the points of insertion of the stubs and the load, adjustment of impedance matching becomes more troublesome.

Another means of the prior art for matching impedance consists of a two-inner conductor matching device, as shown in FIG. 4, wherein use is made of a two-core coaxial line 13_c comprising an outer conductor 13_{c1} and two-inner conductor conductors 13_{c2} and 13_{c3} with their one ends bent as shown. These inner conductors are short circuited by means of a conductive short-circuiting plate A at a distance l_1 from the bent ends whereas the inner conductors and the outer conductor 13_{c1} are short circuited by means of a conductive short-circuiting plate B at a distance l_2 from the bent ends, said short-circuiting plates A and B being mechanically adjustable independently. However, such a matching device requires more complicated adjustment than those shown in FIGS. 2A and 2B.

Furthermore, each of these prior art impedance matching devices is effective only for the variations in the load and is not effective for the variations in the direction of scanning of the beams of electromagnetic waves radiated from respective antenna elements. For this reason, it has been necessary to use phase shifters as above described.

Accordingly, it is an object of this invention to provide a new and improved phased array antenna device wherein the directions of scanning of the beams of electromagnetic waves radiated from respective antennas can be rapidly and smoothly adjusted by electric means which controls the fed terminal voltage of respective antenna elements.

According to this invention, there is provided a phased array antenna device comprising a source of antenna power, a plurality of antenna elements connected to said source at equal spacings, and an impedance transforming four-terminal network connected between each antenna element and said source such that the direction of scanning of the beam of the electromagnetic wave radiated from each antenna element and the voltage of said beam can be varied electrically.

This invention can be more fully understood from the following detailed description when taken in connection with reference to the accompanying drawings, in which:

FIG. 1 is a schematic representation of a prior art phased array antenna device;

FIGS. 2A and 2B are diagrams of prior art impedance matching mechanisms that can be employed in the phased array antenna device shown in FIG. 1;

FIG. 3 shows a detailed construction of the impedance matching mechanism shown in FIG. 2B;

FIG. 4 diagrammatically shows another example of the prior art impedance matching mechanism usable for the phased array antenna device shown in FIG. 1;

FIG. 5 is a diagram of a phased array antenna device embodying this invention;

FIG. 6 and 7 show different types of the impedance transforming four-terminal networks utilized for the phased array antenna device as shown in FIG. 5;

FIG. 8 shows one embodiment of the impedance transforming four-terminal network actually employed in the phased array antenna device shown in FIG. 5;

FIG. 9 is a Smith chart illustrating the impedance variation of the impedance transforming four-terminal network shown in FIG. 8;

FIGS. 10 and 11 show other examples of impedance transforming four-terminal networks;

FIGS. 12A and 12B show modified embodiments wherein the distributed constant line shown in FIG. 11 is substituted by concentrated constant lines;

FIGS. 13 to 16 show different examples of two wire lines of distributed constant; and

FIG. 17 shows still another embodiment of the impedance transforming four-terminal network comprising a suitable combination of lines shown in FIGS. 13 to 16.

The outline of the construction of the phased array antenna device will be given with reference to FIGS. 5 to 7. Like the arrangement shown in FIG. 1 a plurality of antenna elements $33_1, 33_2, 33_3, \dots, 33_m$ are connected in parallel to a source of antenna power 31 through a junction box 32, said antenna elements being spaced from each other by equal spacings d to

form a phased array antenna device. In accordance with this invention, between feed ends of antenna elements 33₁, 33₂, 33₂,...33_m and the junction box 32 are included impedance transforming four-terminal networks 34₁, 34₂,...34_{m11} having characteristics to be described hereunder. If desired, a similar impedance transforming four-terminal network 35 may be connected between the junction box 32 and the source 31.

Here all antenna feeder lines between the junction box 32 and the input terminals of the respective impedance transforming four-terminal networks 34₁, 34₂,...34_{m11} are made to have an equal length $k\lambda g$ by being provided with additional windings W₁, W₂ .... Also, all antenna feeder lines between the output terminals of the respective impedance transforming four-terminal networks and the feed terminals of the corresponding antenna elements 33₁-33_m are made to have an equal length $p\lambda g$ as shown in FIG. 5. k and p are integers, and λg is the wavelength of the antenna current in the antenna feeder lines.

Considering now a column matrix [I] of the antenna current fed to respective antenna elements 33₁,...33_m from the source 31 through the junction box 32, from foregoing description, to scan antenna beams from each of the antenna elements in the θ_0 direction, the following relation should hold.

$$[I] = \begin{bmatrix} I_1 \\ a_2 I_1 e^{-j\phi} \\ a_3 I_1 e^{-j2\phi} \\ \vdots \\ a_i I_1 e^{-j(i-1)\phi} \\ \vdots \\ a_m I_1 e^{-j(m-1)\phi} \end{bmatrix} \quad (1)$$

where $\Phi = (2\pi/\lambda) d \sin\theta$ and a_i represents the amplitude ratio for the i th antenna element 33_i which is determined from the sidelobe level requirement, and I_1 is the current fed to the first antenna element 33₁.

Considering an m row, m column matrix [Z] for the self-radiation impedance and the mutual radiation impedance between m antenna elements and a column matrix [V] for the feed terminal voltage of respective antenna elements 33₁,...33_m the following equations hold.

$$[V] = [Z] \times [I] \quad (2)$$

In equation (2),

$$[V] = \begin{bmatrix} V_1 \\ V_2 \\ \vdots \\ V_i \\ \vdots \\ V_m \end{bmatrix} \text{ and } [Z] = \begin{bmatrix} Z_{11} & Z_{12}, \dots, Z_{1m} \\ Z_{21} & Z_{22}, \dots, Z_{2m} \\ \vdots & \vdots \\ Z_{m1} & Z_{m2}, \dots, Z_{mm} \end{bmatrix}$$

where Z_{ik} ($i + k$) represents the mutual radiation impedance between i th and k th antenna elements and Z_{ii} the self-radiation impedance of the i th antenna element.

$$(i = 1 \sim m, k = 1 \sim m)$$

Accordingly, the feed terminal voltage V_i of the i th antenna element 33_i required to feed an antenna current $I_i \cdot e^{-j(i-1)\phi}$ to it through impedance transforming four-terminal network 34_{i11} can be derived as follows from equation (2).

$$V_i = \sum_{n=1}^m Z_{in} \cdot a_n I_1 \cdot e^{-j(n-1)\phi} \quad (3)$$

Taking the current I_1 flowing through the first antenna element 33₁ as the reference, equation (3) becomes:

$$V_i = I_1 \cdot \sum_{n=1}^m Z_{in} \cdot a_n \cdot e^{-j(n-1)\phi} \quad (4)$$

and the feed terminal voltage V_1 of the first or reference antenna element is expressed by

$$V_1 = I_1 \cdot \sum_{n=1}^m Z_{1n} \cdot a_n \cdot e^{-j(n-1)\phi} \quad (5)$$

The phase of current I_1 flowing through the first antenna element may be arbitrary since patterns of electromagnetic waves radiated from respective antenna elements 33₁,...33_m are determined by the relative values of currents of respective antenna elements.

Where the reference voltage V_0 is directly supplied to the feed terminal of the first or reference antenna element 33₁ from the source of antenna power 31, from equation (5)

$$I_1 = \frac{V_0}{\sum_{n=1}^m Z_{1n} \cdot a_n \cdot e^{-j(n-1)\phi}} \quad (6)$$

Substituting equation (6) into equation (4), we obtain

$$V_i = V_0 \cdot \frac{\sum_{n=1}^m Z_{in} \cdot a_n \cdot e^{-j(n-1)\phi}}{\sum_{n=1}^m Z_{1n} \cdot a_n \cdot e^{-j(n-1)\phi}} \quad (7)$$

Accordingly, the impedance Z_i of the i th antenna 33_i is expressed by

$$Z_i = \frac{V_i}{I_1} = V_0 \cdot \frac{\sum_{n=1}^m Z_{in} \cdot a_n \cdot e^{-j(n-1)\phi} \cdot \sum_{n=1}^m Z_{1n} \cdot a_n \cdot e^{-j(n-1)\phi}}{\sum_{n=1}^m Z_{1n} \cdot a_n \cdot e^{-j(n-1)\phi} \cdot V_0 \cdot a_i \cdot e^{-j(i-1)\phi}} \\ = \frac{\sum_{n=1}^m Z_{in} \cdot a_n \cdot e^{-j(n-1)\phi}}{a_i \cdot e^{-j(i-1)\phi}} \quad (8)$$

Therefore the I_i to be fed to the i th antenna element 33_i is expressed by

$$I_i = \frac{V_i}{Z_i} = V_0 \cdot \frac{a_i \cdot e^{-j(i-1)\phi}}{\sum_{n=1}^m Z_{in} \cdot a_n \cdot e^{-j(n-1)\phi}} = I_1 a_i \cdot e^{-j(i-1)\phi} \quad (9)$$

Thus the phased array antenna device can be constructed by connecting impedance transforming four-terminal networks 34₁,...34_{m11} between feed terminals of respective antenna elements 33₁,...33_m and the junction box 32, the output voltage of said networks satisfying the relation of V_i expressed by equation (7) when the input terminal voltage equals V_0 .

In order to make the voltage impressed upon the input terminals of respective impedance transforming four-terminal networks 34₁,...34_{m11} from the source of antenna power 31 through junction box 32 to be equal to V_0 , it is necessary to select the length of feeder lines between the junction box and respective networks to be equal to integer multiples of the wavelength λg of the antenna current from the antenna power source 31; because all antenna elements are fed in parallel from the same source 31. This means that the same voltage at the junction box is applied to the input terminals of the impedance transforming four-terminal networks 34₁,...34_{m11}.

Examples of impedance transforming four-terminal networks 34₁,...34_{m11} suitable for use in practical applications are described below.

Where each of the impedance transforming four-terminal networks 34₁,...34_{m11} is comprised by two parallel reactance

elements X_1 and X_2 spaced by $\lambda/4$, respectively from feed terminals 41₁ and 42₁ of feeder lines 41 and 42 comprised by two parallel lines (which may be a coaxial line) to the load Z_i or respective antenna elements, as shown in FIG. 6, its basic chain matrix $[F_1]$ is expressed by

$$[F_1] = \begin{bmatrix} \frac{Z_0^2}{X_1 \cdot X_2} - 1 & j \frac{Z_0}{X_2} \\ j \frac{1}{X_1} & -1 \end{bmatrix} \quad (10)$$

Similarly, where each of the impedance transforming four-terminal networks 34₁, ..., 34_{m1} is comprised by three reactances X_1 , X_2 and X_3 respectively spaced by $\lambda/4$ from feed terminals 41₁ and 42₁ of two parallel feeder lines 41 and 42 to the Z_i comprised by the antenna element as shown in FIG. 7, its basic chain matrix $[F_2]$ is expressed by

$$[F_2] = \begin{bmatrix} \frac{Z_0^2}{X_1 \cdot X_2} - 1 & j \frac{Z_0^2}{X_2} \\ j \left(\frac{2}{X_1} - \frac{Z_0^2}{X_1 \cdot X_2} \right) & \frac{X_0^2}{X_1 \cdot X_2} - 1 \end{bmatrix} \quad (11)$$

Thus, in both Figs. 6 and 7

$$V_0 = V_i \left(\frac{Z_0^2}{X_1 \cdot X_2} - 1 \right) + j \frac{Z_0^2}{X_2} I_i \quad (12)$$

Substituting equations (6), and (7) and (9) into equation (12)

$$V_i = V_0 \frac{\sum_{n=1}^m Z_{in} \cdot a_n \cdot e^{-j(n-1)\phi}}{\sum_{n=1}^m Z_{1n} \cdot a_n \cdot e^{-j(n-1)\phi}} \frac{Z_0^2}{X_1 \cdot X_2} - 1 + j \frac{Z_0^2}{X_2} V_0 \frac{a_i \cdot e^{-j(i-1)\phi}}{\sum_{n=1}^m Z_{1n} \cdot a_n \cdot e^{-j(n-1)\phi}} \quad (13)$$

The desired impedance transforming four-terminal network can be realized by determining values of X_1 and X_2 which are necessary to make equal the right- and left-hand terms of equation (13).

Assuming now that

$$\sum_{n=1}^m Z_{in} \cdot a_n \cdot e^{-j(n-1)\phi} = R_i + jX_i \quad (14)$$

$$\sum_{n=1}^m Z_{1n} \cdot a_n \cdot e^{-j(n-1)\phi} = R_N + jX_N$$

$$a_i \cdot e^{-j(i-1)\phi} = \alpha_i + \tau\beta_i$$

$$X_1 = \frac{R_i(X_N + X_i) - X_i(R_N + R_i)}{\alpha_i(R_N + R_i) + \beta_i(X_N + X_i)} = \frac{R_iX_N - R_NX_i}{\alpha_i(R_N + R_i) + \beta_i(X_N + X_i)} \quad (15)$$

$$X_2 = Z_0^2 \frac{\alpha_i R_i + \beta_i X_i}{R_i X_N - R_N X_i} \quad (16)$$

From the above equations can be determined the values of parallel reactances X_1 and X_2 and in consequence the values of the impedance transforming four-terminal circuit networks 34₁ to 34_{m1} according to the present invention as shown in FIGS. 6 and 7 which are used in generating a voltage V_i at the output terminal of each of said networks. If, in this case, there occurs changes in the angle θ at which scanning is conducted by the beams radiated from the antenna elements 33₁ to 33_m, then the values of X_1 and X_2 will be displaced accordingly so that it is necessary to adjust said values to the proper levels

respectively which prevailed before the occurrence of such changes.

FIG. 8 illustrates one example of variable reactance elements X_1 and X_2 adapted for use in a four-terminal network as shown in FIGS. 6 and 7 that can satisfy the relationship shown in FIGS. 6 and 7 and described in connection therewith wherein circuit elements 49 and 50 whose reactance can be varied electrically, such as variable capacitance diodes, are connected between one end 3₁ and 4₁ and between the other end 3₂ and 4₂ of each of two parallel lines 3 and 4 connected in parallel to a predetermined position longitudinally of feeder lines 41 and 42 leading to antenna elements 33₂, ..., 33_m, said feeder lines comprising two parallel lines of $\lambda/4$ long. The circuit elements 49 and 50 are connected to variable DC bias sources 47 and 48, respectively, through circuit elements 43, 44, 45 and 46 which pass direct current and are included when desired. The impedance Z_{lr} of diode 50 connected between output terminals, when viewed from input terminals 3₁ and 4₁, through lines 3 and 4, is expressed by

$$Z_{lr} = \frac{Z_0^2}{Z_{dr}}$$

where Z_0 represents the characteristic impedance of the lines and Z_{dr} the inherent impedance of diode 50.

Considering now Z_{dr} as the pure reactance

$$Z_{dr} = \left(-j \frac{1}{\omega C_{\min.}} \right) \sim \left(-j \frac{1}{\omega C_{\max.}} \right)$$

Therefore, the admittance y_{lr} corresponding to Z_{lr} is expressed by

$$Y_{lr} = \frac{1}{Z_{lr}} = \frac{Z_{dr}}{Z_0^2} = -j \frac{1}{\omega C_{\min.} Z_0^2} \sim \left(-j \frac{1}{\omega C_{\max.} Z_0^2} \right)$$

On the other hand, the impedance Z_{ds} of diode 49 connected between input terminals 3₁ and 4₁ is expressed by

$$Z_{ds} = -j \left(\frac{1}{\omega C_{\min.}} \right) \sim \left(-j \frac{1}{\omega C_{\max.}} \right)$$

and the admittance Y_{ls} by

$$Y_{ls} = \frac{1}{Z_{ds}} = j\omega C_{\min.} \sim j\omega C_{\max.}$$

The admittance Y_{in} as seen from input terminals is given by

$$Y_{in} = Y_{ls} + Y_{lr} = j\omega C_{\min.} \sim (j\omega C_{\max.}) -$$

$$\left[\frac{1}{j\omega C_{\min.} Z_0^2} \sim \left(-\frac{1}{j\omega C_{\max.} Z_0^2} \right) \right]$$

Consequently, Y_{in} can be gradually variable in a range of

from $j\left(\frac{1}{\omega C_{\min.} Z_0^2} - \omega C_{\min.}\right)$ to $j\left(\omega C_{\max.} - \frac{1}{\omega C_{\max.} Z_0^2}\right)$ during

which Y_{in} passes through zero.

In present day variable capacitance diodes $C_{\min.} = 2$ pf. and $C_{\max.} = 0$ pf., so that when assuming the frequency of the antenna current $f_0 = 1,000$ MHz., and $Z_0 = 31.6$ ohms, we obtain

$$Y_{in \min.} = -j \left(\frac{1}{\omega C_{\min.} Z_0^2} - \omega C_{\min.} \right)$$

$$= -j \left(\frac{1}{2 \cdot 10^9 \cdot 10^2 \cdot 2 \cdot 10^{-12}} - 2\pi \cdot 10^9 \cdot 2 \cdot 10^{-12} \right)$$

$$= -j 782.4 \text{ m}\Omega,$$

$$Z_{in \min.} = \frac{1}{-j 782.4 \text{ m}\Omega} = j 1.28\Omega$$

$$Y_{in} \text{ max.} = j(2\pi \cdot 10^9 \cdot 70 \cdot 10^{-12}) - \frac{1}{2\pi \cdot 10^9 \cdot 10^2 \cdot 70 \cdot 10^{-12}}$$

$$= j 417.2 \text{ m}\Omega$$

$$Z_{in} \text{ max.} = \frac{1}{j 417.2 \text{ m}\Omega} = -j 2.4\Omega$$

$$-j\infty \sim -j 2.4\Omega \text{ and } j 1.28\Omega \sim j\infty.$$

$$C \text{ max.} \sim C \text{ min.},$$

$$-j 2.4\Omega \sim 0 \sim j 1.28\Omega$$

Thus, by varying the bias potential it is possible to vary between $-j\infty \sim -j 2.4\Omega$ and $j 1.28\Omega \sim j\infty$. By broadening the variable range of C max. $\sim C$ min., it is possible to decrease the range impossible to realize. While there is a range of $-j 2.4\Omega \sim 0 \sim j 1.28\Omega$ which is impossible to realize, the result of our experiment shows that there is no fear of creating a situation in which it is impossible to match in the actual circuits. Although the standing wave ratio of the circuits deviates somewhat from 1.0 it does not cause any trouble.

In this case, by calculating beforehand the relationship between the scanning angle of the beams of electromagnetic waves radiated from various antenna elements and the bias voltage to be impressed to corresponding ones of variable capacitance diodes 49 and 50 from DC bias sources 47 and 48, it is possible to cause the DC bias sources to fully automatically, smoothly and quickly respond to variations in the load or antenna current frequency by the program control of an electronic computer system.

In this case, where the voltages applied to variable capacitance diodes 49 and 50 from DC bias sources 47 and 48 are varied in n steps it is possible to provide a digital control which varies in $n \times n$ equal steps (in this example $n=4$) around the periphery of a Smith chart as shown in FIG. 9.

FIG. 10 shows another embodiment of this invention wherein the reactance elements X_1 and X_2 (where $X_1=jZ_{ob}\tan\beta l_1$; $X_2=jZ_{ou}\tan\beta l_2$; Z_{ob} = characteristic impedance of balance mode; Z_{ou} = characteristic impedance of unbalance mode; and β = wave number) of impedance transforming four-terminal network as shown in FIG. 4 are respectively comprised of a two inner conductor coaxial line 51 having two inner conductors 51₂ and 51₃ enclosed by an outer conductor 51₁. Each one of inner conductors 51₂ and 51₃ of the coaxial line 51 is divided into small sections of Δl along its length and direct current blocking and coupling condensers C₁₁, C₁₂, C₁₃,...and C₂₁, C₂₂, C₂₃,...having sufficiently small reactance for the antenna current frequency are connected between divided sections. Across alternate sections of inner conductors 51₂ and 51₃ are connected, for example PIN diodes D₁₁, D₁₂,...and between outer conductor 51₁ and one set of alternate sections of inner conductors 51₂ and 51₃ are connected circuit elements L₁₁, L₁₂,...such as inductance coils which permit free flow of direct current but manifest sufficiently high impedance against high-frequency antenna current. One terminal of each of these circuit elements L₁₁, L₁₂,...is connected to respective DC bias sources 53₁, 53₂,...through perforations 52₁, 52₂,...in the outer conductor 51₁. Across the outer conductor 51₁ and the other set of alternate sections of inner conductors 51₂ and 51₃ are connected PIN diodes D₂₁, D₂₂,...and across these sections are connected circuit elements L₂₁, L₂₂,...such as inductance coils which permit free flow of direct current but manifest sufficiently high impedance against the antenna current. Similarly, one terminal of these circuit elements are connected to respective variable DC bias sources 55₁, 55₂,...through perforations 54₁, 54₂,...in the outer conductor 51₁. If desired, bypass condensers 56₁, 56₂,...may be connected between DC bias sources 53₁, 53₂,...and 55₁, 55₂,...and the outer conductor 51₁, as shown in FIG. 10.

With this arrangement by applying a bias voltage to the PIN

diode of any one section from the associated DC bias source in order to maintain said particular diode in short-circuited condition but to maintain other diodes in open circuited condition, it is possible to short circuit both inner conductors 51₂ and 51₃ or outer conductor 51₁ and both conductors at every two sections. When compared with prior impedance matching devices wherein the impedance thereof has been varied mechanically, the impedance matching network can provide faster and smoother impedance matching adjustment in response to variations in the load or antenna current.

FIG. 11 shows another embodiment of this invention wherein the reactance elements X_1 and X_2 of impedance transforming four-terminal network as shown in FIGS. 6 and 7 are comprised respectively of a feeder line 62 mounted on a grounded plate 61. Equally spaced-apart diodes 63₁, 63₂, 63₃,...are connected to the feeder line 64₁, 64₂, 64₃,...are connected between respective diodes and grounded plate 61 to form bypass paths to high-frequency transmission current. The other terminals of the condensers are connected to variable DC bias sources 65₁, 65₂, 65₃,...

With these reactance elements, since the diodes are rendered in their on or off state according to the value of bias voltage supplied thereto from corresponding DC bias sources 65₁, 65₂, 65₃,...either one of the diodes is rendered on while others are all in their off state. Denoting by d the length of the feeder line between its feed terminal and a point to which a diode is connected, the input reactance of this circuit is given by

$$Z_{in}=Z_0 \tan\beta d \quad (17)$$

where Z_0 represents the characteristic impedance of the line and $\beta=2\pi/\lambda$.

When another diode is rendered on while remaining diodes are off, the input reactance of the line for different lengths d can be similarly given. Thus, the input reactance can be varied by varying the spacing between diodes according to equation (17). Thus, it is possible to vary the impedance represented by the Smith chart in the same manner as above described.

In the actual construction of a circuit as shown in FIG. 11, if the line were too long it may be possible to decrease its length by replacing equivalent concentrated L, C elements for the distributed circuit constants as shown in FIGS. 12A and 12B.

FIG. 13 represents still another embodiment of the reactance elements X_1 and X_2 of the impedance transforming four-terminal network as shown in FIGS. 6 and 7. Considering two lines 1 and 2 coupled to each other by the distributed constants and having terminals (1.1), (1.2), (2.1) and (2.2) and by denoting their terminal voltages and currents by (V₁, I₁), (V₂, I₂), (V₃, I₃) and (V₄, I₄) respectively, the fundamental equations for this eight-terminal network

are given by

$$\begin{aligned} V_1 &= V_3 \cos \beta l + j Z_{00} \sin \beta l [-I_3 - K I_4] \\ I_1 &= -I_3 \cos \beta l + j \frac{\sin \beta l}{(1 - K^2) Z_{00}} [V_3 - K V_4] \\ V_2 &= V_4 \cos \beta l + j Z_{00} \sin \beta l [-K I_3 - I_4] \\ I_2 &= -I_4 \cos \beta l + j \frac{\sin \beta l}{(1 - K^2) Z_{00}} [-K V_3 + V_4] \end{aligned} \quad (18)$$

Denoting the characteristic impedance of a balanced system by Z_{ob} and that of an unbalanced system by Z_{ou} ,

$$K = \frac{4 \frac{Z_{ou}}{Z_{ob}} - 1}{4 \frac{Z_{ou}}{Z_{ob}} + 1} \quad (19)$$

$$Z_{00} = Z_{ou} + \frac{Z_{ob}}{4}$$

where β represents the propagation constant of said two systems and l the length thereof.

If, as shown in FIG. 14, terminal (1.2) is opened, terminal (2.2) short circuited and terminal (2.1) connected to an impedance Z_2 , we obtain

$$\begin{aligned} V_2 &= -I_2 Z_2 \\ I_3 &= 0 \\ V_4 &= 0 \end{aligned} \quad (20)$$

Substituting equation (20) into equation (18),

$$V_1 = V_3 \cos \beta l + j Z_{00} \sin \beta l (-K I_4)$$

$$I_1 = j \frac{\sin \beta l}{(1 - K^2) Z_{00}} V_3$$

$$V_2 = j Z_{00} \sin \beta l (-I_4)$$

$$I_2 = -I_4 \cos \beta l + j \frac{\sin \beta l}{(1 - K^2) Z_{00}} (-K V_3)$$

Solutions of this equation are

$$I_1 = -\frac{1}{K} \left(\cos \beta l + j \frac{Z_{00}}{Z_2} \sin \beta l \right) I_4$$

$$V_1 = j \frac{Z_2 Z_{00} \cos^2 \beta l - K^2 Z_{00} + j(1 - K^2) Z_{00} \sin \beta l \cos \beta l}{K Z_2 \sin \beta l} I_4 \quad (22)$$

and the input impedance Z_{in1} of this circuit is expressed by

$$\begin{aligned} Z_{in1} &= \frac{V_1}{I_1} \\ &= j \frac{-K^2 Z_2 Z_{00} (1 - K^2) Z_{00} \sin \beta l \cos \beta l + Z_2 Z_{00} \cos^2 \beta l}{-j Z_{00} \sin^2 \beta l - Z_2 \cos \beta l \sin \beta l} \end{aligned} \quad (23)$$

Considering now a special case wherein $\beta l = \pi/2$,

$$Z_{in1} (\beta l = \pi/2) = K^2 Z_2 \quad (24)$$

This is equivalent to a case in which $K^2 Z_2$ is connected to the input terminal.

As shown in FIG. 15, if an impedance Z_3 is connected to terminal (1.2), and terminals (2.1) and (2.2) are short circuited, then

$$\begin{aligned} \frac{V_2}{I_2} &= \frac{V_4}{I_4} = 0, \quad V_2 = V_4 = 0 \\ \frac{V_3}{I_3} &= Z_3 \end{aligned} \quad (25)$$

therefore

$$\begin{aligned} V_1 &= V_3 \cos \beta l - j Z_{00} \sin \beta l [-I_3 - K I_4] \\ I_1 &= -I_3 \cos \beta l + j \frac{\sin \beta l}{(1 - K^2) Z_{00}} V_3 \\ 0 &= j K_{00} \sin \beta l [-K_3 I_3 - I_4] \\ I_2 &= -I_4 \cos \beta l + j \frac{\sin \beta l}{(1 - K^2) Z_{00}} (-K V_3) \end{aligned} \quad (26)$$

from this

$$\begin{aligned} I_4 &= -K I_3, \\ I_2 &= -K I_1 \end{aligned} \quad (27)$$

therefore

$$Z_{in3} = \frac{V_1}{I_1} = (1 - K^2) Z_{00} \frac{Z_3 \cos \beta l + j(1 - K^2) Z_{00} \sin \beta l}{(1 - K^2) Z_{00} \cos \beta l + j Z_3 \sin \beta l} \quad (28)$$

Consequently, the line functions as a transmission line having

a characteristic impedance $(1 - K^2) Z_{00}$ and a length l .

When, as shown in FIG. 16, terminal (2.2) is connected to an impedance Z_4 , and terminals (1.2) and (2.1) are open following relations hold.

$$I_2 = I_3 = 0 \quad \frac{V_4}{-I_4} = Z_4$$

$$V_1 = V_3 \cos \beta l + j Z_{00} \sin \beta l (-K I_4)$$

$$I_1 = j \frac{\sin \beta l}{(1 - K^2) Z_{00}} [V_3 - K V_4] \quad (29)$$

$$V_2 = V_4 \cos \beta l + j Z_{00} \sin \beta l (-I_4)$$

$$0 = -I_4 \cos \beta l + j \frac{\sin \beta l}{(1 - K^2) Z_{00}} [-K V_3 + V_4]$$

20 The input impedance Z_{in4} in this case is given by

$$Z_{in4} = \frac{V_1}{I_1} = \frac{1}{\sin \beta l} \frac{j K^2 Z_{00} + Z_4 \sin \beta l \cos \beta l - j Z_{00} \cos^2 \beta l}{\cos \beta l + j \frac{Z_4}{Z_{00}} \sin \beta l} \quad (30)$$

$$\text{where } \beta l = \frac{\pi}{2},$$

30

$$Z_{in4} (\beta l = \pi/2) = \frac{K^2 Z_{00}^2}{Z_4} \quad (31)$$

35 This is equivalent to a case wherein impedance Z_4 is connected to a line having a characteristic impedance $K Z_{00}$ and a length $\lambda/4$.

When Z_4 equals infinity, Z_{in4} becomes zero and short circuited.

40 Then, as shown in FIG. 17, circuits of FIGS. 14 and 16 are interconnected.

First assuming that Z_2 is equal to infinity, then Z'_{in} is zero, and Z'_{in} is infinity, Z_{in} is $K^2 Z_1$, when Z_1 is varied from $-j\infty$ to $-j0$, Z_{in} also changes from $-j\infty$ to $-j0$, Z_2 is varied from ∞ under short circuited condition of Z_1 .

If, at this time, Z_2 is also varied from $-j\infty$ to $-j0$, as has been described in connection with FIG. 15, the section connected to impedance Z_1 and the next succeeding section comprise a transmission line having an overall characteristic impedance

50 Z_0 and a length of $\lambda/2$ so that Z_{in} is equal to Z'_{in} .

If $K^2 Z_{00}^2 / Z_2 = Z_0^2 / Z_2$ and if Z_2 is varied from $-j\infty$ to $-j0$, from equation (31), Z_{in} will change from $j0$ to $j\infty$.

55 As above described, the circuit shown in FIG. 17 provides a circuit wherein the impedance can be varied from $-j\infty$ to $j\infty$ passed through zero by varying Z_1 and Z_2 from $-j\infty$ to $-j0$.

60 If in this case, variable capacitance diodes are utilized as impedances Z_1 and Z_2 and if variable DC bias voltages are applied to these diodes through grounded conductors, it is possible to provide still another reactance element for impedance transforming four-terminal network for use in this invention that can attain the same objects as the previous embodiments.

We claim:

1. A phased array antenna device comprising a source of antenna power; a plurality of equally spaced antenna elements energized by said source; and a plurality of impedance transforming four-terminal networks, each of which is connected between said source and the feed terminals of respective antenna elements, each one of said networks being constructed to satisfy the equation:

$$V_i = V_o \frac{\sum_{n=1}^m Z_{in} \cdot an \cdot e^{-j(n-1)\phi}}{\sum_{n=1}^m Z_{kn} \cdot an \cdot e^{-j(n-1)\phi}}$$

where:

V_o = the voltage applied to the input terminal of said impedance transforming network,
 V_i = the i th output voltage appearing at the output terminal of said impedance transforming network,
 Z_{in} = the self-radiation impedance and mutual radiation impedance of the i th antenna element,
 Z_{kn} = the self-radiation impedance and mutual radiation impedance of the k th antenna element,
 a_n = the amplitude ration which is given from the sidelobe requirement, and
 $O = (2\pi/\lambda)^2 d \sin \theta$,

where:

d = the spacing between adjacent ones of said antenna elements,
 λ = the wavelength of the antenna current from said source, and
 θ = the scanning direction of radiated beams from each of said antenna elements.

2. A phased array antenna device according to claim 1 wherein each one of said impedance transforming four-terminal networks comprises a pair of parallel lines of one-fourth wavelength connected in series with a feeder line leading to one of said antenna elements, variable reactance elements connected to the opposite ends of said parallel lines and variable DC voltages connected to said variable reactance elements.

3. A phased array antenna device according to claim 1 wherein each one of said impedance transforming four-terminal networks comprises a coaxial line connected in series with a feeder line leading to each antenna element, said coaxial line including an outer conductor and two inner conductors connected in parallel, a first group of variable reactance elements connected across said inner conductors at spaced intervals along the length thereof, a first group of variable DC bias sources connected to said variable reactance elements, a second group of variable reactance elements connected between said outer conductor and said inner conductors in an interleaved fashion with the reactance elements of said first group, and a second group of variable DC bias sources connected to said second group of reactance elements.

4. A phased array antenna device according to claim 1 wherein each one of said impedance transforming four-terminal networks comprises a line parallel to a grounded plate

and connected in series with a feeder line leading to each antenna element, a plurality of variable reactance elements connected to said line at spaced intervals along the length thereof, and a plurality of variable DC bias sources connected to said variable reactance elements.

5. A phased array antenna device according to claim 1 wherein each one of said impedance transforming four-terminal networks comprises two lines of distributed constants connected in series with a feeder line leading to each antenna element, each of said lines having a length equal to one-fourth of the wavelength of the antenna current, variable reactance elements respectively connected between opposite ends of said lines, and variable DC bias sources connected to said variable reactance elements.

10 15 6. A phased array antenna device according to claim 4 wherein said line parallel to said grounded plate of said impedance transforming four-terminal network is comprised by a line of concentrated circuit constants so as to decrease the length thereof.

7. A phased array antenna device according to claim 2 wherein said variable reactance elements comprise variable reactance diodes.

8. A phased array antenna device according to claim 3 wherein said variable reactance elements comprise diodes.

20 25 9. A phased array antenna device according to claim 4 wherein said variable reactance elements comprise diodes.

10. A phased array antenna device according to claim 5 wherein said variable reactance elements comprise diodes.

11. A phased array antenna device according to claim 2 30 35 wherein the bias voltages supplied to said variable reactance elements from said variable DC bias sources are varied by a program control of an electric computer system.

12. A phased array antenna device according to claim 3 wherein the bias voltages supplied to said variable reactance elements from said variable DC bias sources are varied by a program control of an electric computer system.

35 40 13. A phased array antenna device according to claim 4 wherein the bias voltages supplied to said variable reactance elements from said variable DC bias sources are varied by a program control of an electric computer system.

14. A phased array antenna device according to claim 5 wherein the bias voltages supplied to said variable reactance elements from said variable DC bias sources are varied by a program control of an electric computer system.
